UNITED STATES PATENT OFFICE.

MARTIN J. OSTUL, OF GHENT, MINNESOTA.

STRAINER-SUPPORT AND SCREEN.

1,290,303.

Specification of Letters Patent. Patented Jan. 7, 1919.

Application filed November 21, 1916. Serial No. 132,675.

To all whom it may concern:

Be it known that I, MARTIN J. OSTUL, a citizen of the United States, and a resident of Ghent, in the county of Lyon and State of Minnesota, have invented certain new and useful Improvements in Strainer-Supports and Screens, of which the following is a specification.

My present invention relates to devices for supporting strainers at the mouths of containers and screening said mouths against ingress of flies, or other foreign matter. The principal objects of my invention are to provide devices of the character described which will effectively support the strainers usually of the funnel type, at the mouths of containers, such as pails or separator tanks, and retain them against accidental displacement; supports which may be quickly placed into or removed from operative relation to the containers; and screens associated with the supports which may be quickly attached to or removed from the supports, said screens capable of preventing ingress of foreign matter into the containers about the strainers when placed in position.

Other objects of my invention are to provide devices of the character described which are simple in construction, inexpensive to manufacture, durable, and light in weight.

Further objects of my invention will appear in the following detailed description, taken in connection with the accompanying drawing, forming a part of this specification, and in which drawing:

Figure 1 is a perspective view of a strainer support constructed according to my invention and disposed in operative relation to a pail.

Fig. 2 is a plan view of a screen constructed according to my invention.

Fig. 3 is an enlarged central vertical longitudinal sectional view through the support and showing the screen as applied thereto.

Fig. 4 is a perspective view of a detail of the screen.

Fig. 5 is an enlarged sectional view on the line 5—5 of Fig. 2.

In the drawing, where similar characters refer to similar parts throughout the views, A designates a container, by way of example, a pail; B a strainer support at the mouth of said container; and C a screen carried by said support.

Referring first to the support B, I prefer

to form the same of a single strip of metal and primarily double the same upon itself, substantially midway of its ends, providing complementary sections 6. These sections, 60 for a portion of their length from the junction 7, form a stem 8, as by being in engagement with one another, and twisted as indicated at 9. Each section 6 is arcuated where it springs from said stem providing 65 an annular shaped main body 10 to embrace a portion of the funnel. Continuing from said main body 10, the sections extend in parallel relation for a short distance, preferably in engagement one with the other, 70 and in the longitudinal axis of stem 8, after which they are bent in opposite directions, preferably at right angles, with the terminal portions 11 adapted to embrace the top of the container A. These sections 6 are secured together, as by a rivet 12 at that portion of body 10 opposite to stem 8. Each terminal portion 11 may be adapted to grip the container A, as by being slit longitudinally to provide stems 13 and 14, these stems 75 being bent in such a manner that stem 13 is of hook shape and adapted to rest upon the upper margin of the container A and engage the outer side of its wall, while the stem 14 is bent downwardly and outwardly 80 with respect to main body 10 to engage the inner side of the wall of the container.

If desired, the support may be made of metal having a slight spring action, or the stems 13 and 14 may be spring-tempered and it is preferred to so arrange said stems one 90 with respect to the other that when placed into operative relation to the container, they are moved out of a normal position causing their free end portions to bite slightly the 95 wall of the container, which prevents accidental displacement of the support with respect to the container. It is preferred to arrange the stem 8 so that its major portion is in a substantially horizontal plane, when 100 in use, and rests upon the upper margin of the container A.

Referring now to the screen C, it comprises a frame 15, netting 16, carried by said frame, and devices 17 for securing said netting to the frame, and also adapted to secure the screen to the support B when desired.

The frame 15 may be conveniently formed of wire to provide an outer rim 18 and an inner rim 19, said rims connected together in any suitable manner, as by a coupling piece 20. The netting 16 may be of copper

wire or other material, preferably non-corrosive. The devices 17 may consist of strips of metal, each strip curled at one end portion as indicated at 21 to overlie the netting 16 and hold the same in intimate contact with the outer rim 18, the other end portion of each device 16 being split as indicated at 22, one stem 23 being curled to overlie and retain the netting in intimate contact with the inner rim 19, while the other stem 24 extends downwardly and is provided with an offset 25, which may be engaged beneath the main body 10 of the support B, when the screen is assembled in operative relation to said support. Each device 17 may be of spring material, or the stem 24 may be spring-tempered, if desired.

The inner rim 19 is preferably of substantially the same diameter as main body 10 of support B, and the netting 16 may be secured to the frame 15 by soldering in addition to the securing devices 17, it being understood that the netting extends between the rims 18 and 19 and is turned about said rims, as clearly shown in Fig. 5 of the drawing.

When assembling the screening in operative relation to the support B, the stems 24 are sprung inwardly toward the axis of rim 19 and the screen is forced downwardly upon the support until the offset 25 of stem 24 springs beneath the main body 10 of the support. This secures the screen to said support and aligns the axes of rim 19 and main body portion 10. The tubular portion of the strainer may then be passed through the opening of main body 10 and screen C after the device has been disposed into operative relation to the container A.

It is to be observed that the device may be quickly assembled into operative relation to the container and is held against accidental displacement owing to the engagement of the stems 13 and 14 with the wall of the container.

Changes in details may be made without departing from the spirit or scope of my invention; but,

I claim:

1. A strainer support and screen for the mouths of containers comprising in combination, a support including an annular main body portion to receive a portion of the strainer, a frame including an outer rim and an inner annular rim of substantially the same diameter as the said annular main body portion of said support, netting carried by said frame extending between and turned over the rims thereof, and a plurality of strips of metal, each with one end portion turned to secure said netting to said outer rim and its other end portion split to provide stems, one of said stems turned to secure said netting to said inner rim, with the

other stem extending downwardly from said rim and adapted to be hooked to the said annular main body portion of said support. 65

2. A strainer support comprising an annular main body, supporting arms radiating from said body, one of said supporting arms being forked to form spaced container engaging arms having their outer ends split to form stems, certain of said stems having their outer terminals curved for engaging over the edge of a container and the remaining stems being bent downwardly and curved outwardly for terminal engagement with the interior of a container below its edge. 70 75

3. A strainer support comprising an annular main body, supporting arms radiating from said body, one of said supporting arms being forked to form spaced container engaging arms having their outer ends split to form stems, certain of said stems having their outer terminals curved for engaging over the edge of a container and the remaining stems being bent downwardly and curved outwardly for terminal engagement with the interior of a container below its edge, a frame including an outer and an inner rim, netting carried by and extending between said rims, said innermost rim being slightly larger than said annular main body, and means for securing netting to said rims and attaching said inner rim to said annular main body. 80 85 90 95

4. A strainer support and guard for the mouths of containers comprising an annular main supporting body adapted to support a strainer, inner and outer annular rims, a netting carried by and extending between said rims, means for attaching said rims to said body, said inner rim being positioned over said annular body whereby an annular netting will surround said main body to prevent the passage of foreign substance into a container exteriorly of the main body. 100 105

5. A strainer support comprising an annular body, supporting arms radiating from said body, one of said supporting arms being forked to form spaced container engaging arms having their outer ends split to form stems, certain of said stems having their outer terminals curved for engaging over the edge of a container and the remaining stems being bent and curved outwardly for terminal engagement with the interior of a container below its edge, inner and outer annular rims, a netting carried by and extending below said rims, means for attaching said rims to said body, said inner rim being positioned over said annular body whereby said annular netting will surround said main body to prevent the passage of foreign substance into a container exteriorly of the main body. 110 115 120
